CLAIM

The ornamental design for a tripod mount for camera lens, as shown and described.

DESCRIPTION

FIG. 1 is a front perspective view of a tripod mount for camera lens showing my new design;

FIG. 2 is a rear perspective view thereof;

FIG. 3 is a front view thereof, the rear view being a mirror image of FIG. 3;

FIG. 4 is a top plan view thereof;

FIG. 5 is a left side view thereof; and,

FIG. 6 is a referential view showing the article in use.

The features shown in broken lines in the drawings depict environmental subject matter only and form no part of the claimed design.
